**CASING FOR REFRIGERATION SYSTEM
CONDENSING UNITS OR THE LIKE**

William C. Martin, Jr., Syracuse, Walter W. Hoyle,
Fayetteville, and Fred V. Honnold, Jr., North Syracuse,
N.Y., assignors to Carrier Corporation, Syracuse, N.Y.

Continuation-in-part of abandoned design application Ser.
No. 233,852, Mar. 10, 1972. This application July 2,
1973, Ser. No. 375,566

Term of patent 7 years

Int. Cl. D23—04

U.S. Cl. D23—139

FIG. 1

FIG. 2

FIG. 3

FIG. 4

FIG. 1 is a top view of a casing for refrigeration system condensing units or the like showing our new design.

FIG. 2 is a side elevational view of the casing shown in FIG. 1.

FIG. 3 is an elevational view of the rear of the casing shown in FIG. 1, and

FIG. 4 is an elevational view of the front of the casing shown in FIG. 1.

This is a continuation-in-part of design application Ser. No. 233,852, filed Mar. 10, 1972, and now abandoned.

We claim:

The ornamental design for a casing for refrigeration system condensing units or the like, substantially as shown and described.
